Primary Examiner — Jerry Shiuan-Hua Hsu(74) *Attorney, Agent, or Firm* — Nixon & Vanderhye PC(57) **CLAIM**

The ornamental design for a member of a load bin cover as shown and described.

DESCRIPTION

FIG. 1 is a top, right side perspective view of a first embodiment of a member of a load bin cover;

FIG. 2 is a bottom, right side perspective view thereof;

FIG. 3 is a front plan view thereof;

FIG. 4 is a rear plan view thereof;

FIG. 5 is a right side plan view thereof;

FIG. 6 is a left side plan view thereof;

FIG. 7 is a top plan view thereof;

FIG. 8 is a bottom plan view thereof;

FIG. 9 is an enlarged front plan view thereof; and,

FIG. 10 is a top perspective view thereof, shown in a condition of use.

The dash-dot broken lines depicting break lines in the article, and any portions of the member of the load bin cover between the break lines, form no part of the claimed design. The dashed broken lines illustrating a load bin cover in FIG. 10 depict environmental structure that forms no part of the claimed design.
